UNITED STATES PATENT OFFICE.

CAMPBELL ALLISON, OF ST. LOUIS, MISSOURI.

RAILWAY RAIL.

Application filed February 15, 1923. Serial No. 619,227.

To all whom it may concern:

Be it known that I, CAMPBELL ALLISON, a citizen of the United States, residing at the city of St. Louis, and State of Missouri, have invented a new and useful Railway Rail, of which the following is a specification.

This invention relates to railway rails, and consists in the novel construction hereinafter disclosed.

An object of the invention is to provide a rail composed of a plurality of sections so arranged and combined as to form a practically continuous rail.

Another object of the invention is to provide a rail of a plurality of sections assembled to equalize the stresses and strains to which the rail is subjected in use so as to eliminate to a high degree the vibration of the rail and to impart to it substantial rigidity.

Another object of the invention is to provide a rail of a plurality of sections arranged to be assembled together in a continuous structure, with means for interlocking the sections to impart to it rigidity.

Additional advantages of the structure will be apparent from the following detailed description taken in connection with the accompanying drawing, in which

Fig. 1 is an isometric view of a rail section including the invention.

Fig. 2 is a cross section of the assembled rail, the plate connecting the base with the web of the tread being in elevation.

Fig. 3 is an isometric view of the tread section and web.

Fig. 4 is a detailed view of the connecting member.

Fig. 5 is a fragmentary view of one of the strut members of the rail.

Fig. 6 is a fragmentary view of the base section.

The rail structure includes a base plate 1. At each side edge the plate 1 is up-turned and bent inwardly to form substantially L-shaped longitudinal flanges 2. On the upper face of the plate 1 and substantially intermediate its side edges is an angular flange 3 that extends the full length of the plate.

The body portion of the rail structure

comprises a tread 4, said tread portion having depending flanges 5 at its lower side edges in which are under-cut grooves 6 for receiving strut or brace members as will be more fully described hereinafter. A web extends downward from the under face of the tread, said web including a relatively thick portion 7 having downwardly tapering side walls, and developing into a relatively thin portion 8, below which is an enlarged portion 9 from which an L-shaped off-set part 10 extends. The body portion is preferably formed from high grade steel so that it will be durable under frictional wear.

The rail structure further includes a connecting plate 11 having a channel 12 in one face thereof adjacent to the bottom edge, one wall of which is extended to form a flange 13.

The side braces or struts of the rail structure comprise angular plates bent to form a horizontal portion 14 and a relatively wide inwardly inclined wall 15, developing into a relatively narrow vertical portion 16, from which extends an outwardly inclined wall 17.

It will be understood that the separate elements of the rail structure formed as described are made in standard lengths and that by assembling the several elements a continuous rail may be built, without the use of supplemental fastening devices, as the sections interlock to form the rail structure.

The method of assembly of the several elements is as follows: The base section is positioned on the road bed, and the brace or strut members are assembled therewith by seating the member 14 in the respective channels formed by the flanges 2 at each side of the base. The connecting plate section is assembled with the base by interlocking the flanges 3 and 13. The body section is heated to a sufficient degree to expand the same, and is assembled endwise with the remaining elements, the parts being so designed that, when expanded, the body portion will move into place in association with the other elements. The body portion when heated may be moved between the strut members in such a manner that the

upper edges of the strut members will seat in the channels 6, the vertical walls 16 seating against the walls of the section 8 of the body portion, and the walls 15 constituting braces for supporting the rail structure against lateral strains.

It will be noted that the plate 11 fits into the recess formed by the offset wall 10 of the body portion, the lower flange of the body portion resting on the upper face of the flange 3, and the flange of the body portion extending into the channel 12. In this manner a vertical brace for the entire rail structure is provided.

When the body portion shrinks upon cooling the parts will be interlocked so as to be practically rigid throughout the length of the rail structure.

It will be noted that the rail structure comprises five separate elements and that in assembling the structure each of the elements is arranged so as to break joint with the other elements, thus avoiding any weak point in the continuous rail.

It will be understood that the rail structure may be secured to the ties by spikes as in the ordinary separate rails now in common use, but that the assembly of the rails requires no supplemental fastening devices, the elements thereof constituting mutual means for the rail structure.

I am aware that the invention may be modified in certain particulars without departing from the spirit and scope thereof.

What I claim and desire to secure by Letters Patent is:—

1. A continuous rail, comprising a base plate having side retaining flanges, a body portion, strut members connected with the base and with the body portion, and a vertical connecting plate between the body portion and the base section holding them from vertical separation.

2. A continuous rail, comprising a body portion including a tread and a depending web, a base plate, side strut members arranged to be connected with the plate at their lower edges and to constitute lateral braces for the web portion of the body and connected with the tread portion of the body at their upper edges, a connecting plate between the web of the body portion and the face of the base plate holding them from vertical separation.

3. A rail, comprising a base section, a body section including a tread and a depending web, side sections positioned between said base and said tread section and being connected with said sections respectively, and a separate connecting plate intermediate the base section and the body section locking the body section in connection with the plate and preventing them from separating vertically.

4. A rail, comprising a base section, a

body section including a tread and web, resilient side sections formed with angular walls and connected respectively with the base section and with the tread section and abutting against the vertical wall of the web so as to constitute side braces, and means for holding the web from vertical separation from the base section.

5. A rail, comprising a base section and a body section, said base section having retaining flanges at its side edge, struts interlocking with said flanges of the base section and extending inwardly to abut against the body section and outwardly above said contact points and interlocking with the tread at their upper edges, and a device for locking the body sections with the base.

6. A continuous rail, comprising a base section having side retaining flanges and an L-shaped flange on the top face thereof intermediate said side flanges, a body portion comprising a tread, the under face of which is provided with downwardly inclined walls and an offset web below said tread, side strut members supported at their lower edges by the side flanges of the base and having upwardly inclined walls developing into vertical walls for contact with the web of the body portion, outwardly inclined walls lying adjacent to the lower walls of the tread, recesses in the tread for receiving the upper edges of said strut members, and a connecting plate arranged in a vertical plane between the web and the plate, said plate connecting with the intermediate flange of the base section.

7. A rail structure, comprising a base plate, a body portion including a tread and a web, side strut members connected to the plate and the tread and constituting lateral braces, and a connecting plate between the web and the base plate, said parts being designed for assembly when the body portion is in a heated condition so that when said body portion contracts an interlocking engagement between the parts will be effected.

8. A rail structure, comprising a base plate, a body portion including a tread and a web, side strut members connected to the plate and the tread and constituting lateral braces, and a connecting plate between the web and the base plate, said parts being designed for assembly when the body portion is in a heated condition so that when said body portion contracts an interlocking engagement between the parts will be effected, and said separate elements being assembled together so that they will break joints throughout the structure.

9. A rail structure, comprising a plurality of separate sections arranged so that the joints thereof are spaced; said sections including a body portion, a base plate, side strut members and a connecting plate between the body portion and the base plate,

all of said members being interlocked by shrinking the body portion after the same has been assembled with the remaining elements of the structure.

5 10. A rail section, including a base, a body portion having a web extending in a vertical direction and resting upon the base, an-

gular side strut members having inwardly inclined walls connected respectively with the base and tread sections, and a locking device 10 holding the web and the base section from vertical separation.

CAMPBELL ALLISON.
